United States Patent Office.

JOHN PETTENGILL, JR., OF LISBON, NEW HAMPSHIRE.

Letters Patent No. 66,385, dated July 2, 1867

IMPROVED CAR-COUPING.

The Schedule referred to in these Letters Patent and making part of the same.

TO ALL WHOM IT MAY CONCERN:

Be it known that I, JOHN PETTENGILL, Jr., of Lisbon, Grafton county, New Hampshire, have invented a new and improved Car-Coupling; and I do hereby declare that the following is a full, clear, and exact description thereof, which will enable others skilled in the art to make and use the same, reference being had to the accompanying drawings, forming part of this specification, in which—

Figure 1 is a longitudinal central section of my improved car-coupling.

Figure 2 is a horizontal section of the same.

Similar letters of reference indicate corresponding parts.

This invention relates to a self-acting car-coupling, which is so arranged that the link will be held between the elastic sides of the coupling-box, so that the link is prevented from rattling, and is always held firmly in any desired position. Provision is also made that high and low cars can be coupled. The coupling-pin rests upon a pallet or horizontal upper arm of an elbow-lever which is pivoted to the coupling-box by a pin which passes through the lower part of the vertical arm of said elbow-lever. The weight of the horizontal arm and of the coupling-pin keeps the whole lever forward; but as soon as the link strikes any portion of the vertical arm of the lever, the same will be bent back, and the horizontal part be withdrawn from under the coupling-pin, which will drop through the link. As soon as the pin is raised again, and the link withdrawn, the weight of the horizontal arm will bring the elbow-lever again into the aforesaid position.

A represents a coupling-box, made of suitable material, and of the usual form. Across the front opening of the box is placed a bar, B, which divides the entrance into an upper and lower part, so that the links C will have less play up and down. The sides of the box are open, and springs D D are arranged therein, which are firmly secured to the rear end of the box, their front ends forming elastic sides of the box. As is clearly shown in figs. 1 and 2, these springs do not extend quite to the front end of the box, but leave a strong bumper frame in front. The faces of the springs D in the coupling-boxes may be covered with India rubber, leather, or other suitable elastic material. E is an L-shaped lever, of which the horizontal arm *a* is on top, and points forward, as shown in the drawing. The vertical arm *b* of the lever is pivoted by a pin, *c*, to the sides of the box A, the said pin passing through the lower part of the arm *b*, and as near to the rear edge of the same as possible. The whole lever E will thus be made to lean forward by its own gravity, as shown in fig. 1, and the end of the arm *a* will close the hole *d* in the upper part of the box A, as shown. F is the coupling-pin, which rests upon the end of the arm *a*, and passes through the hole *d*, as shown in fig. 1. When the link C is pushed into the box, it strikes the arm *b* of the lever E, and throws it back, so as to release the pin F, which will then drop down through the link, as shown on the right-hand side of fig. 1. As soon as the pin is raised and the link removed, the arm *a* will drop forward and close the hole *d* again, as shown in the left-hand side of fig. 1. The joint weight of the arm *a* and pin F will hold the said arm *a* in position forward, so that no rattling or shaking motion of the car will be able to swing the lever E back and drop the pin F spontaneously. The springs D D clamp that end of the link which is in the box firmly, and prevent the same from moving sideways unless when turning the curve. They will then give as much as necessary, and will at once resume their original position when the curve is passed. They act as elastic cheeks for the sides of the box A, and hold the link in any desired position.

Having thus described my invention, what I claim as new, and desire to secure by Letters Patent, is—

The combination of the box A, link C, springs D, and elbow-plate E, with each other, all made and operating substantially as herein shown and described.

JOHN PETTENGILL, JR.
